(57) **CLAIM**

The ornamental design for a water bottle, as shown and described.

DESCRIPTION

FIG. 1 is a perspective view of the present invention; FIG. 2 is a front view of the present invention, the back side view, right side view and left side view being a mirror image thereof;

FIG. 3 is a top view of the present invention; and, FIG. 4 is a bottom view of the present invention.

The broken lines in all Figures immediately adjacent the solid lines represent the bounds of the claim, and the broken lines and the area within the broken lines represent unclaimed portions of the present invention. None of the broken lines form a part of the claimed design.
